UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,800, dated March 20, 1883.

Application filed January 25, 1883. Term of patent 3½ years.

To all whom it may concern:

Be it known that I, WINTHROP L. JACOBS, of East Orange, Essex county, New Jersey, have invented a new and original Design for 5 Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is filled in with a system of small leaves with irregular stem-connections, as shown in the photograph. This ground is traversed by irregular running stems that bear along their length or on short branching stems various irregular and fanciful flower and leaf-like figures, symmetrical and otherwise, as is 15 clearly shown in the photograph. Prominent among these are the figures A, B, C, D, E, and F, of various shapes, as shown. The figures 20

that are thus disposed in the foreground, along the running stems referred to, are larger in size than the leaf forms that constitute the background. 25

I claim—

1. The design for a ground for a carpet, consisting of the ground *a*, substantially as shown and described. 30

2. The design for a carpet, consisting of the figures A, B, C, D, E, and F, and the intervening smaller figures and connecting-stems, substantially as shown and described. 35

3. The design for a carpet, consisting of the figures A, B, C, D, E, and F, and the intervening smaller figures and connecting-stems, and the ground *a*, substantially as shown and described. 35

WINTHROP L. JACOBS.
